UNITED STATES PATENT OFFICE.

JOHN QUINCY REED, OF NEW YORK, N. Y., ASSIGNOR TO THE BUTTERICK PUBLISHING COMPANY, (LIMITED,) OF SAME PLACE.

DESIGN FOR A LADY'S WRAP.

SPECIFICATION forming part of **Design No. 14,454**, dated November 27, 1883.

Application filed September 26, 1883. Term of patent 3½ years.

To all whom it may concern:

Be it known that I, JOHN QUINCY REED, of the city, county, and State of New York, have invented and produced a new and original Design for a Pattern of a Lady's Wrap, (numbered 8,864;) and I do hereby declare that the engraved prints accompanying this specification convey to any one accustomed to using paper patterns a clear understanding of how a garment made up by the pattern will appear.

The design exhibits two sections for the body—one for each side—and each section being shown half-fitted. The back is shown

plaited high at the center. The shape rounds away below the closing in front and outlines deep ovals on the hips. A standing collar and wide sleeves are added.

What I claim as my invention, and desire to secure by Letters Patent, is—

The design for a lady's wrap, as shown in the engraved prints accompanying this specification.

JOHN QUINCY REED.
